UNITED STATES PATENT OFFICE.

EDISON E. RANDALL, OF KANKAKEE, ILLINOIS, ASSIGNOR TO PARAMOUNT KNITTING COMPANY, OF CHICAGO, ILLINOIS, A CORPORATION OF ILLINOIS.

KNITTING-MACHINE NEEDLE.

1,121,287.

Specification of Letters Patent. Patented Dec. 15, 1914.

Application filed February 19, 1914. Serial No. 819,614.

To all whom it may concern:

Be it known that I, EDISON E. RANDALL, a citizen of the United States, and resident of Kankakee, county of Kankakee, State of Illinois, have invented an Improvement in Knitting-Machine Needles, of which the following description, in connection with the accompanying drawing, is a specification, like characters on the drawing representing like parts.

This invention relates to a knitting machine, and particularly to the needle and the means for operating it, and is an improvement upon the invention disclosed in Patent No. 1,096,945, granted May 19, 1914, to Pope and Randall (now application Serial No. 535,323, filed December 28, 1909). A knitting machine needle of this type is made up of two separate independently movable members one formed to present the usual hook and termed the "hook member," and the other performing the function of the usual latch and termed the "latch member." The two needle members are mounted in superimposed grooves formed in the needle cylinder or needle bed with the groove for the latch member narrower than that for the hook member so that the two members are kept entirely separate.

The present invention is especially concerned with two features of improvement, first, in means for preventing the point of the latch member from passing the back or rear face of the hook member, and second, in the provision of clearance between the forward portion of the shank of the latch member, and the opposing wall of its groove.

When the longitudinal movement of the needle is a considerable one such for example as that which takes place in the cylinder needles of an ordinary knitting machine, there is nothing in certain positions of the needle member to limit the transverse movement of the needle members except the construction of the machine itself. Under these circumstances by reason of the hook member swinging away from the needle bed or from other causes the needle members are liable to become separated transversely and upon the retracting movement of the hook member the point of the latch member will pass to the rear of the hook member, not only rendering the knitting imperfect but frequently breaking the needle. It is important also that clearance

shall be provided between the latch member and the rear wall of the groove in which it is located to take care of the fibers and dirt which might otherwise clog the groove and hinder or prevent the movement of the latch member in its groove. The present invention eliminates these difficulties in a simple and efficient manner.

The nature of the invention will appear more fully from the accompanying description and drawings and will be particularly defined in the appended claims.

The drawings represent a preferred form of needle embodying the invention together with so much of an ordinary knitting machine as is involved in connection therewith.

In the drawings, Figure 1 is a view chiefly in vertical cross-section of the upper portion of the needle and cam cylinders of an ordinary type of plain circular knitting machine showing needles of the preferred form of this invention in position; Fig. 2 is an enlarged detail partially in longitudinal cross-section of the upper portion of the hook and latch members of a preferred form of needle embodying the invention; Fig. 3 is a view similar to Fig. 2 showing the members in different position; Fig. 4 is a view in transverse cross-section taken on the line A—A, Fig. 2; Fig. 5 is a view similar to Fig. 4, showing a slightly different form of latch member; and Fig. 6 is a view similar to Fig. 4 showing another form of latch member.

The general construction of the machine and needle herein illustrated is similar to that disclosed in the aforesaid patent so that it is unnecessary to describe it in detail.

The needle cylinder is indicated at 1 and the cam cylinder at 2. The hook member of the needle 3 is of practically the same form as the corresponding member of the ordinary pivoted latch needle comprising the hooked end 4, the shank and the butt 5, all of which parts vary in length, shape and proportion, according to the particular style of needle. The hook member 3 is slotted transversely at 6 near its forward end, and this slot is preferably made in a form of a saw kerf entering the hook member from the front or face so that the end walls of the slot converge rearwardly and present at the rear surface of the hook member shoulders 7 and 8. The hook member is

22 mounted to slide longitudinally in a groove 9 formed in the usual manner in the exterior surface of the needle cylinder

3 sheet metal and of a thickness which will allow it to move readily within the slot 6 of the hook member comprises a head 11 and a tail 12. It is mounted to slide in a longitudinal auxiliary groove 13 formed in the 10 needle cylinder directly and centrally back of or beneath the hook member groove 9. The head of the latch member is provided with upper and lower or forward and rear cam surfaces 14 and 15, respectively, and 15 with upper and lower or forward and rear shoulders 16 and 17, respectively. The tail of the latch member at its lower or rearward end is preferably bent as indicated at 18 to 20 secure frictional engagement with the walls of its groove.

25 The operation of the needle is fully explained in the aforesaid patent. Starting with the position shown on the left hand side of Fig. 1, or in Fig. 2, the yarn is fed beneath the hook 4, the hook member is retracted by the cam 5 until the shoulder 7 engages the cam surface 14 when the latch member is moved laterally or transversely of the hook member within the 30 slot so as to project the latch end or point 19 in position to cover the hook, as shown in Fig. 3; the shoulder 7 is then in engagement with the shoulder 16, and the two members are then retracted or moved downwardly 35 until the limit of movement is reached. When the hook member rises or is moved forward it moves independently of the latch member for a distance and then the shoulder 8 engages the cam surface 15 moving the 40 latch member laterally or transversely rearward until the shoulder 8 contacts with the shoulder 17 when the parts are again in the position shown in Fig. 2.

45 The hook member especially in a cylinder needle has a considerable longitudinal movement and a greater movement than is necessary to secure the coöperative action of the latch and hook. This results in a separation longitudinally of the end 19 of the latch 50 and the shoulder 7 of the hook member, as shown, for example, in Fig. 2, so that when the hook member is given its downward or retracting movement the end 19 of the latch is likely to pass to the rear of the hook member, and consequently to the rear of the shoulder 7. This may be caused by a transverse movement of the latch member in its groove or by the hook member being tipped away 55 from the needle cylinder in the operation 60 of the machine, or by other conditions. When it happens the latch member obviously fails to coöperate with the hook, the knitting is rendered imperfect and the needle itself is usually broken and serious damage 65 may result to the machine. One feature of

this invention is, therefore, the provision of means for preventing the latch end from passing the rear of the hook member. This is secured in the construction illustrated by providing the head of the latch member with a projection adapted to engage the face of the hook member, and thus positively prevent the latch member from moving transversely to the rear of the hook member to such an extent as to cause the end 19 of the 70 latch to pass behind the shoulder 7. This projection may be formed in various ways. In the preferred form illustrated in Figs. 1 to 4 inclusive, it is shown as a small rivet 20, in Fig. 5 it is shown as an integral projection 21 from the head of the latch member such as would be formed by a punch, while in Fig. 6 it is shown at 22 as formed by the head of the latch member being bent at right angles to itself to overlap one side of the 80 face of the hook member. It is obvious that the particular construction which may be employed is capable of wide variation to 85 secure the desired result.

90 Knitting machines as is well known are subject to accumulation of dust and dirt such as arising from the fine fibers of the yarn which may clog the working parts unless taken care of. One feature of the invention consists in providing a clearance between the 95 latch member and its groove so as to prevent this rather fine and delicate part from becoming clogged. This is secured by inclining the rear face of the shank or tail of the latch member at its upper portion, or in 100 other words, reducing the width of the shank or tail of the latch member at its upper or forward portion toward its upper or forward end. This will be seen in Fig. 1 where it will be noted that the forward or upper end of the tail of the latch member is narrower in width than the lower or rearward end, thus providing the clearance 105. This is possible because by the other feature 110 of the invention means are provided which limit the rearward transverse movement of the latch member. Otherwise this clearance could not be provided because the latch member might move rearwardly at its upper end and the latch end would then pass behind the shoulder 7 rendering the needle 115 inoperative. When the projection 20, 21 or 22 is in engagement with the face of the hook member the distance between the said projection and the rear of the shank of the latch member is less than that between the 120 face of the hook member and the rear wall of the latch member groove.

125 It will be seen that the two main features of this invention work together to secure an improved form of the separate latch needle rendering that instrument highly efficient, and eliminating the difficulties which have been pointed out to its successful use under certain conditions.

Having fully described my invention, what I claim as new and desire to secure by Letters Patent is:

1. A knitting machine needle comprising a longitudinally slotted hook member, a latch member having relative longitudinal and transverse bodily movement through the slotted portion of said hook member into and out of coöperative relation therewith, and means to prevent the end of the latch from passing behind the back of the hook member.
2. A knitting machine needle comprising a longitudinally slotted hook member, a latch member having relative longitudinal and transverse bodily movement through the slotted portion of said hook member into and out of coöperative relation therewith, and a projection on said latch adapted to engage the face of the hook member and prevent the end of the latch from passing behind the back of the hook member.
3. A knitting machine needle comprising a longitudinally slotted hook member, a latch member having relative longitudinal and transverse bodily movement through the slotted portion of said hook member into and out of coöperative relation therewith, and means for preventing the end of the latch member from passing to the rear of the forward wall of the slot of the hook member when the said latch end and wall are separated longitudinally.
4. In a knitting machine, a knitting machine needle comprising a hook member slotted longitudinally, a latch member projecting into said slot and provided with cam surfaces coöperating respectively with the walls of said slot whereby upon the forward movement of the hook member the latch member will be drawn into the slot, and upon the retraction of the hook member will be projected through the slot to cover the hook, a projection on the latch member to engage the face of the hook member and prevent the end of the latch member from passing behind the forward wall of said slot when the said latch end and wall are separated longitudinally.
5. In a knitting machine, a needle comprising a longitudinally slotted hook member, a separate latch member movable longitudinally and laterally in said slot to cover and uncover the hook, a needle bed provided with superimposed grooves one for each of said members, the forward portion of the tail of the latch member being of less width than the depth of its groove whereby clearance is provided, and means for preventing the end of the latch member from passing to the rear of the hook member.
6. In a knitting machine, a needle comprising a longitudinally slotted hook member, a separate latch member movable longitudinally and laterally in said slot to cover and uncover the hook, a needle bed provided with superimposed grooves one for each of said members, the forward portion of the tail of the latch member being of less width than the depth of its groove whereby clearance is provided, and a projection on the latch member adapted to engage the face of the hook member and limit the rearward lateral movement of the latch member.
7. In a knitting machine, a needle comprising a longitudinally slotted hook member, a separate latch member movable longitudinally and laterally in said slot to cover and uncover the hook, a needle bed provided with superimposed grooves, one for each of said members, the width of the latch member being reduced toward its forward end to provide clearance between the forward portion of the latch member and the rear wall of its groove, and means causing the needle members to engage in the latter portion of their retracting movements to limit the rearward lateral movement of the latch member and preserve the said clearance.
8. In a knitting machine, a knitting machine needle comprising a hook member slotted longitudinally, a latch member projecting into said slot and provided with oppositely disposed cam surfaces and shoulders coöperating respectively with the walls of said slot whereby upon the forward movement of the hook member one cam surface will act to withdraw the latch member into the slot, one shoulder will act to cause the forward movement of the latch member by the hook member, and upon the retraction of the hook member the other cam surface will act to cause the latch member to be projected from the slot to cover the hook and the other shoulder will act to cause the latch member to be retracted by the hook member without contacting with the hook, means for effecting the movement of the hook member, a projection on the latch member extending over the face of the hook member and acting to prevent the end of the latch from passing in the rear of the hook member.

In testimony whereof, I have signed my name to this specification, in the presence of two subscribing witnesses.

EDISON E. RANDALL.
